CLAIM

The ornamental design for a staple cartridge for surgical instrument, as shown and described.

DESCRIPTION

FIG. 1 is a side perspective view of a first embodiment of a staple cartridge for surgical instrument, showing our new design;

FIG. 2 is a top plan view thereof;

FIG. 3 is a bottom plan view thereof;

FIG. 4 is a side elevation view thereof;

FIG. 5 is another side elevation view thereof;

FIG. 6 is an enlarged front elevation view thereof;

FIG. 7 is an enlarged rear elevation view thereof;

FIG. 8 is a side perspective view of a second embodiment of a staple cartridge for surgical instrument, showing our new design;

FIG. 9 is a top plan view thereof;

FIG. 10 is a bottom plan view thereof;

FIG. 11 is a side elevation view thereof;

FIG. 12 is another side elevation view thereof;

FIG. 13 is an enlarged front elevation view thereof; and,

FIG. 14 is an enlarged rear elevation view thereof.

The wire frame lines shown throughout the views are intended to indicate surface contour.
